UNITED STATES PATENT OFFICE.

WILLIAM F. LEONARD, OF COLUMBUS, OHIO.

TOY VEHICLE.

1,296,977.

Specification of Letters Patent. Patented Mar. 11, 1919.

Application filed May 13, 1918. Serial No. 234,080.

To all whom it may concern:

Be it known that I, WILLIAM F. LEONARD, a citizen of the United States, residing at Columbus, in the county of Franklin and 5 State of Ohio, have invented a certain new and useful Improvement in Toy Vehicles, of which the following is a specification.

The invention relates more particularly 10 to vehicles for the use of small children in which propulsion is effected by pushing with the feet on the ground and has for one of its objects to so construct the device that it can be adjusted to adapt the vehicle for the 15 use of the smallest children and at the same time permit the use of sufficiently large wheels to render the operation of the vehicle easy.

Another object of the invention is to provide simplified means for adjusting the seat 20 so that the device can be used by children of considerably varying size or so as to be useful to the same child as it grows larger.

A further object is to so construct the device 25 that it can be propelled by the rider in either the standing or sitting position, thus also enabling the rider to give momentum to the vehicle before occupying the seat.

30 And still another object is to provide improved means for journaling the steering post.

The invention is embodied in the example herein shown and described, the features of 35 novelty being finally claimed.

In the accompanying drawing—

Figure 1 is a view in side elevation of the right hand side of the vehicle.

Fig. 2 is a section on the line II—II of 40 Fig. 1 looking toward the rear.

Fig. 3 is a fragmentary detail view showing the reverse of the seat-attaching means as shown in Fig. 1.

Fig. 4 is a section on the line IV—IV of 45 Fig. 1 looking down and showing in detail the boxing for the steering post.

In the views 5 designates the single steering wheel which is journaled in a fork on the lower end of a steering post 6 having 50 a suitable handle 6^a at its upper end.

7, 8 designate the rear wheels which are 55 journaled on a suitable metallic axle 8 supplemented with a wooden foot piece 8^a. This wooden foot piece is rounded off at

each side to receive the foot of the user 55 when starting or riding in a standing position.

The steering post is swiveled between a collar 30 and the upper end of the fork in a boxing comprising two blocks 9. Connecting these blocks 9 and the lower side of the axle is an inclined bar or reach 10, said bar forming the seat support. At its forward end the reach 10 is secured by means of bolts 11 between the blocks 9, and 60 at its rear end the reach is rabbeted and grooved to fit against the lower side of the metallic axle and the supplementary wooden foot piece 8^a where it is held by a metallic strap 12 that is secured to the reach and 65 bent at its ends around the end of the wooden foot piece 8^a. The metallic axle 8 passes through a hole in the strap 12 where the latter passes around each end of the wooden foot piece. 70

At their forward ends the blocks 9 are connected by a threaded bolt 13 having a nut 13^a which can be tightened or loosened to compensate for swelling or contraction of the post due to dampness or dryness and 75 permit the free turning of the steering post without wobbling.

14 designates the seat which is provided with a double or two-part stem 15 and 15^a inclined forward to the plane of the seat 85 to straddle the reach, the part 15 being provided with a series of parallel grooves 16 any of which receives the cross piece of a yoke 17. The legs of the yoke 17 are threaded and passed through the inclined 90 reach to receive an appropriately perforated strap 18 and securing nuts 19. By sufficiently loosening the nuts 19 and shoving the yoke transversely of the reach the seat may be raised or lowered and again secured 95 as shown. I increase the depth to which the seat may be lowered by grooving out the seat as at 14^a so that the seat at that point straddles the inclined reach.

In order that a vehicle of the type herein 100 referred to shall be practical it is necessary that the wheels be comparatively large. It will be observed that with my construction, which includes the inclined reach mounted above the forward axle and under the rear 105 axle, it is practical to use comparatively large wheels and yet place the seat low so that a small child or baby can propel him-

self with his feet on the ground or floor while seated in the seat. By making the seat adjustable the device is adapted to the child as it grows larger; and moreover it is 5 not necessary for the dealer to carry several sizes in stock so as to supply large and small children.

The forms of the parts can be changed without departing from the gist of the invention as claimed.

What I claim is:

1. A child's toy vehicle comprising, in combination, rear supporting wheels and axle, a front steering wheel and steering post therefor, a reach or seat support extending from above the front wheel to the axle of the rear wheels, a seat having a stem affixed thereto and extending downwardly and forwardly therefrom at an acute 20 angle to the plane of the seat and at an

acute angle to the line of the steering post and means adjustably connecting said stem to the reach permitting the raising and lowering of the seat with reference to the reach and causing said seat to approach the steering post when lowered and recede from said steering post when raised.

2. A child's toy vehicle comprising, in combination, rear supporting wheels and axle, a front steering wheel, a reach or seat support extending from above the front wheel to the axle of the rear wheels, a seat having a stem for adjustable connection with said reach and means for securing said stem to said reach in adjusted position consisting of a movable yoke engaging both the stem and the reach and means for securing said yoke to said stem and reach.

WILLIAM F. LEONARD.
